STRUCTURE FOR REMOVABLY SUPPORTING SLATS IN A VENETIAN BLIND

Glenn L. Sherwood, Benton Harbor, Mich.

Original application June 16, 1945, Serial No. 599,775. Divided and this application January 16, 1950, Serial No. 138,720

12 Claims. (Cl. 160—173)

1

This invention relates to improvements in structure for removably supporting slats in a Venetian blind.

The invention disclosed herein has been divided from my copending application, Serial No. 599,775, filed June 16, 1945, for Venetian Blind and Tape Construction.

The principal objects of this invention are:

First, to provide novel means for effectively retaining the slats of a Venetian blind in proper laterally spaced position on the ladder tapes of the blind while still permitting easy disengagement of the individual blind slats for cleaning or other purposes.

Second, to provide novel means for adapting the cross straps of Venetian blind ladders to retain slotted blind slats in properly aligned position relative to the lift cords of the blind assembly.

Third, to provide inexpensive and easily assembled means for adapting standard Venetian blind ladders for use with blind slats having cord receiving slots opening to one of their edges.

Fourth, to provide a ladder structure for a Venetian blind which eliminates the necessity for forming apertures or holes in the cross straps of the ladder when the ladder is used in combination with removable blind slats having cord receiving slots opening to their edges.

Other objects and advantages of my invention will be apparent from a consideration of the following description and claims and the attached drawings of which there are two sheets.

Fig. 1 illustrates a fragmentary perspective view of one form of my Venetian blind construction.

Fig. 2 is a fragmentary left end elevational view of the blind structure shown in Fig. 1.

Fig. 3 is an end elevational view of the structure shown in Figs. 1 and 2 with the slats in tilted position.

Fig. 4 is a fragmentary perspective view of the ladder structure shown in Figs. 1 to 3.

Fig. 5 is a fragmentary vertical longitudinal cross sectional view through the blind taken along the plane of the line 5—5 in Fig. 2.

Fig. 6 is a fragmentary horizontal cross sectional view through the blind assembly and taken along the plane of the line 6—6 in Fig. 5.

Fig. 7 is a fragmentary vertical longitudinal cross sectional view similar to Fig. 5 and illustrating a modified form of blind assembly.

Fig. 8 is a perspective view of the cord retaining plate employed in the modified assembly shown in Fig. 7.

2

Fig. 9 is a fragmentary horizontal cross sectional view through a still further modified form of my blind assembly.

Fig. 10 is a perspective view of a pair of the cord retaining plates employed in the assembly shown in Fig. 9.

It has previously been proposed to provide Venetian blinds in which the individual blind slats are removable from the blind supporting ladders by reason of the slats being formed with laterally opening slots to receive the lift cords which extend vertically through the several slats and usually between the opposite tapes of each ladder. Blinds of this general construction and without further modification have been found objectionable in that when the blinds are tilted in the well known fashion the lift cords approach the open ends of the slots in the blind slats and often become disengaged from the slots. Then when the blind is again tilted to bring the slats into horizontal position the lift cords engage the edges of the slats and prevent the slats from returning to the desired horizontal position. In my above mentioned copending application I have disclosed structure for preventing this accidental disengagement of the individual blind slats by providing cross straps on the ladders having elongated holes formed therein to receive the lift cords of the blind and to vertically support the blind slats. The end portions of the cross straps at the ends of the holes therein are thus positioned across and form closures for the open ends of the slots in the blind slats. Then when the blind assembly is tilted the end edges of the holes in the cross straps engage the lift cords and prevent them from moving laterally with respect to the blind slats sufficiently to pass through the open ends of the slots in the slats.

The foregoing structure has been found to have one commercial disadvantage in that the manufacture of Venetian blind ladders with cross straps having elongated holes therein is expensive. This appears to be due to the present inability of the manufacturers of Venetian blind ladders to form an elongated hole in fabric cross straps and produce the straps at an economical low price. The several forms of my present invention provide economical means for providing closures on the cross straps of a Venetian blind ladder for the ends of the slots in the blind slats.

Fig. 1 illustrates a portion of a Venetian blind which includes a plurality of slats 1 tiltably supported by a pair of ladders 2. Each of the lad-

ders includes the spaced ladder tapes 3 connected by cross straps 4. Preferably the cross straps 4 are fabric straps of relatively narrow width compared to the width of the tapes 3 and are secured in alternately staggered and laterally spaced relation near the opposite edges of the tapes by means of the tabs 5 which are either stitched or secured by adhesive to the opposed faces of the ladder tapes.

The staggered position of the cross straps 4 provides an open space vertically in the center of each ladder through which the lift cords 6 of the blind assembly are threaded. The individual slats 1 which rest upon the cross straps are provided with laterally spaced transversely opening slots 7 which permit the individual slats to be tilted or twisted upwardly until the lift cords are disengaged from the slots 7 after which the individual slat can be removed endwise from the ladders for cleaning or replacement.

In order to prevent accidental disengagement of the cords 6 from the slots 7 during tilting motion of the blind, as described above, I have provided a plurality of retaining plates 8 which are secured to and supported by the cross straps 4. The plates 8 are of relatively rigid construction and can be formed of thin metal or thermoplastic material or any other substance having the necessary rigidity. Each of the plates 8 has an elongated hole 9 formed therein transversely of the blind structure or longitudinally of the cross straps 4. The hole 9 is formed near the center of the plate and the plate approximates the length of the cross strap so that the plate can be secured to either the right or left cross straps of a ladder structure. The plate may be secured to the cross strap by adhesive 10 (see Fig. 5) or by adhesion of the thermoplastic material of the plate itself or by other suitable means.

With the plates 8 in position the ends of the holes 9 will engage the lift cords 6, as at 11 in Fig. 3; when the blind is tilted to prevent the lift cord from moving out of the slots 7 in the blind slats.

Figs. 7 and 8 illustrate a modified form of retaining plate and method of attaching the plate to the cross straps of the ladder. The plate 8A is of substantially the same size and shape as the plate 8 in Figs. 1 to 5 and has an elongated hole 9A formed therein. The plate 8A is provided with a return bend flange 12 along one edge thereof which is designed to fit over and be crimped against the cross straps 4 of the ladder. In order to make the plate 8A attachable to either the right or left cross straps on the ladders, the hole 9A is longer than the hole 9 and is symmetrical to both ends of the plate.

Figs. 9 and 10 illustrate a further modified form of plate which may be used in place of the plates 8 or 8A. The plates 8B are of L-shape construction having one branch 13 approximately equal in length to the length of the plates 8 and another branch 14 approximately equal in length to the width of the ladder tapes. The plates 8B are provided with return bend flanges 15 along the outer edge of the long arms 13 and are adapted to be secured to the cross straps by crimping the flanges 15 and arms 13 about the straps. It will be noted that the arms 14 are of approximately the same width as the end portions of the plates 8 and 8A at the ends of the slots 9 so that the arms 14 lie across and close the ends of the slots 7 in the blind slats when the plates and slats are assembled in a blind structure. Right and left hand plates 8B

are provided as shown in Fig. 10 so that the arms 13 may overlie the cross straps 4 on both the right and left sides of the ladder tapes.

All forms of my cord retaining plates operate in the same manner in cooperation with the cross straps and slats of a Venetian blind to hold the blind slats in properly aligned relationship to the ladder structures. While I have disclosed three modified forms of slat aligning structure 10 I do not intend to limit my invention to the specific forms illustrated as other variations of the plates or clips and arrangement of the cross straps of the ladders may be devised which will fall within the scope of the claims.

Having thus described my invention, what I claim as new and desire to secure by Letters Patent is:

1. In a Venetian blind having laterally spaced double tape supporting ladders with vertically extending lift cords positioned between the tapes of the ladders the combination of, cross straps connecting the tapes of each ladder, said straps being of relatively narrow width and secured to said tapes in vertically staggered positions near the opposite edges of the tapes, a plurality of blind slats removably supported on said cross straps and having elongated slots opening to their edges to receive said lift cords, and cord retaining plates secured by adhesive along their side edges to said cross straps, said cord retaining plates having elongated holes formed therein and extending longitudinally alongside said cross straps and embracing said lift cords, the ends of said retaining plates at the ends of said holes constituting closures for the outer ends of the slots in said blind slats.

2. In a Venetian blind having laterally spaced double tape supporting ladders with vertically extending lift cords positioned between the tapes of the ladders the combination of, cross straps connecting the tapes of each ladder, said straps being of relatively narrow width and secured to said tapes near the edges of the tapes, a plurality of blind slats removably supported on said cross straps and having elongated slots opening to their edges to receive said lift cords, and cord retaining plates secured along their side edges to said cross straps, said cord retaining plates having elongated holes formed therein and extending longitudinally alongside said cross straps and embracing said lift cords, the ends of said retaining plates at the ends of said holes constituting closures for the outer ends of the slots in said blind slats.

3. In a Venetian blind having laterally spaced double tape supporting ladders with vertically extending lift cords positioned adjacent to the tapes of the ladders the combination of, cross straps connecting the tapes of each ladder, said straps being positioned adjacent to said cords, a plurality of blind slats removably supported on said cross straps and having elongated slots opening to their edges to receive said lift cords, and cord retaining plates secured to said ladders and lapped between said cross straps and said slats, said cord retaining plates having elongated holes formed therein and extending longitudinally alongside said cross straps to receive said lift cords, the ends of said retaining plates at the ends of said holes constituting closures for the outer ends of the slots in said blind slats.

4. In a Venetian blind having laterally spaced double tape supporting ladders with vertically extending lift cords positioned adjacent to the tapes of the ladders the combination of, cross

straps connecting the tapes of each ladder, said straps being positioned adjacent to said cords, a plurality of blind slats removably supported on said cross straps and having elongated slots opening to their edges to receive said lift cords, and cord retaining plates secured to said ladders and lapped between said cross straps and said slats, said cord retaining plates extending longitudinally alongside said lift cords and having laterally extending end portions constituting closures for the outer ends of the slots in said blind slats.

5. In a Venetian blind having laterally spaced double tape supporting ladders with vertically extending lift cords positioned adjacent to the ladders the combination of, cross straps connecting the tapes of each ladder, said straps being secured to said tapes in vertically spaced positions alongside of the cords, a plurality of blind slats removably supported on said cross straps and having elongated slots opening to their edges to receive said lift cords, and cord retaining plates secured to said cross straps, said cord retaining plates having elongated holes formed therein and extending longitudinally alongside said cross straps and embracing said lift cords, end portions of said retaining plates at the ends of said holes constituting closures for the outer ends of the slots in said blind slats.

6. In a Venetian blind having laterally spaced double tape supporting ladders with vertically extending lift cords positioned adjacent to the ladders the combination of, cross straps connecting the tapes of each ladder, said straps being secured to said tapes in vertically spaced positions alongside of the cords, a plurality of blind slats removably supported on said cross straps and having elongated slots opening to their edges to receive said lift cords, and cord retaining plates secured to said ladders and lapped along said straps, said cord retaining plates having elongated holes formed therein and extending longitudinally alongside said cross straps and embracing said lift cords, end portions of said retaining plates at the ends of said holes constituting closures for the outer ends of the slots in said blind slats.

7. In a Venetian blind having laterally spaced double tape supporting ladders with vertically extending lift cords positioned adjacent to the ladders the combination of, cross straps connecting the tapes of each ladder, said straps being secured to said tapes in vertically spaced positions alongside of the cords, a plurality of blind slats removably supported on said cross straps and having elongated slots opening to their edges to receive said lift cords, and cord retaining plates having return flanges along their side edges clamped over to said cross straps, said cord retaining plates having elongated holes formed therein and extending longitudinally alongside said cross straps and embracing said lift cords, end portions of said retaining plates at the ends of said holes constituting closures for the outer ends of the slots in said blind slats.

8. In a Venetian blind having laterally spaced double tape supporting ladders with vertically extending lift cords positioned adjacent to the ladders the combination of, cross straps connecting the tapes of each ladder, said straps being secured to said tapes in vertically spaced positions alongside of the cords, a plurality of blind slats removably supported on said cross straps and

having elongated slots opening to their edges to receive said lift cords, and cord retaining plates having return flanges along their side edges clamped over to said cross straps, said cord retaining plates extending longitudinally alongside said lift cords, end portions of said retaining plates constituting closures for the outer ends of the slots in said blind slats.

9. In a Venetian blind having laterally spaced double tape supporting ladders with vertically extending lift cords positioned between the tapes of the ladders, cross straps connecting the tapes of each ladder, said straps being of relatively narrow width and being secured to said tapes in vertically staggered positions on opposite sides of the cords, a plurality of blind slats removably supported on said cross straps and having elongated slots opening to their edges thereof to receive said lift cords, and L-shaped cord retaining plates having return bend flanges along a side edge of one of their arms clamped over said cross straps, said cord retaining plates extending longitudinally alongside said cords and having laterally extending arms at the ends of said first arms constituting closures for the outer ends of the slots in said blind slats.

10. In a Venetian blind having laterally spaced double tape supporting ladders with vertically extending lift cords positioned adjacent to the ladders the combination of, cross straps connecting the tapes of each ladder, said straps being of relatively narrow width and being secured to said tapes in vertically staggered positions on opposite sides of the cords, a plurality of blind slats removably supported on said cross straps and having elongated slots opening to their edges to receive said lift cords, and L-shaped cord retaining plates secured along their side edges to said cross straps, said cord retaining plates having laterally extending arms on one end projecting across and constituting closures for the outer ends of the slots in said blind slats.

11. In a Venetian blind having laterally spaced double tape supporting ladders with vertically extending lift cords positioned adjacent to the ladders the combination of, cross straps connecting the tapes of each ladder, said straps being secured to said tapes in vertically spaced positions adjacent to the cords, a plurality of blind slats removably supported on said cross straps and having elongated slots opening to their edges to receive said lift cords, and L-shaped cord retaining plates secured to said tapes and lapped along said cross straps, said cord retaining plates having laterally extending arms on one end projecting across and constituting closures for the outer ends of the slots in said blind slats.

12. In a Venetian blind having laterally spaced double tape supporting ladders with vertically extending lift cords positioned adjacent to the ladders the combination of, cross straps connecting the tapes of each ladder, a plurality of blind slats removably supported on said cross straps and having transverse slots opening to their edges to receive said lift cords, and cord retaining plates secured to said ladders, said cord retaining plates extending laterally from said cross straps through vertical planes through said lift cords and said slots in said slats to constitute closures for the outer ends of the slots with respect to said cords.
